UNITED STATES PATENT OFFICE

2,400,531

RADIO APPARATUS

Howard J. Benner, Longmeadow, Mass., assignor
to The F. W. Sickles Company, Chicopee, Mass.,
a corporation of Massachusetts

Original application May 24, 1944, Serial No.
537,129. Divided and this application March 24,
1945, Serial No. 584,644

6 Claims. (Cl. 250—16)

This invention relates to improvements in radio apparatus and is directed more particularly to condensers and intermediate frequency assemblies.

This application is a division of application Ser. No. 537,129 filed by me May 24, 1944.

One object of the invention is the provision of a fixed condenser which is particularly adapted for use in connection with intermediate frequency transformers and the like.

Another object of the invention is the provision of an intermediate frequency transformer which is characterized by novel components including the condenser.

Various other novel features and advantages of the invention will be hereinafter more fully referred to in connection with the following description of the invention in the form at present preferred.

In the drawing:

Fig. 1 is a side elevational view of the components of an intermediate frequency transformer embodying the novel features of the invention;

Fig. 2 is a perspective view of the condenser of the invention;

Fig. 3 is an elevational view of the condenser shown in Fig. 2; and

Fig. 4 is a side elevational view of an intermediate frequency transformer embodying the novel features of the invention.

Referring now to the drawing more in detail, the invention will be fully described.

A condenser is represented by 2 which includes a body 4 of plastic material molded to enclose a condenser from which extends terminals 6. The material of the body may be Bakelite, rubber or some other suitable composition which is used for molding condensers and the like.

The condenser may include thin sheets of dielectric material such as mica which carry or have therebetween thin metal plates. The metal plates are alternately connected to the spaced terminals 6 and is accomplished by a metal clip 8 secured to each terminal which is bent around the ends of the condenser elements.

The condenser may consist of thin plates of mica which may carry a metal plating or coating with thin strips of metal foil extending from the plating to the clips 8 alternately so that one set of metal plating is connected to one terminal while the other set is connected to the other terminal.

The terminals 6 may have reduced portions 10

around which wires may be wound that are soldered to the said terminals.

An inner face 12 of the condenser is provided with a projection 14 and a socket 16. A half-hole 18 is provided in the upper part of said face and a relatively larger half-hole 20 is provided in the lower part thereof.

In one way two such condensers are employed by placing their inner faces together so that the projection of each face is received in the socket of the other. In this relation the half-holes provide an upper hole and a lower hole.

A bracket 22 has a horizontal part 24 and depending arms 26 provided with tapped holes 28.

15 A bushing 30 has an upper part 32 that extends through bracket part 24 and is spun over so as to be fast to the bracket 22. This part 32 of the bushing fits in the half-holes 18 of the condensers when they are in back to back relation. A lower part 34 of the bushing is received in the half-holes 20 of the condensers when in back-to-back relation and is spaced inwardly from the sides of the half-holes. A collar portion 31 of bushing abuts the upper side of half-holes 20.

The bushing 30 is internally screw threaded to threadedly receive a screw 36 and a lock washer 38 threadedly engages said screw 36.

20 The condenser 2 has a vertical groove 7 in its outer face so that when a pair of condensers are in back to back relation the parts 26 of the bracket are received in the grooves 7.

A tube 42 having a relatively thin wall and made from suitable material so as to act as a coil support carries one or more inductance coils 44 and 46 which may be the primary and secondary of an intermediate frequency transformer or the like. The upper end portion of tube 42 is receivable in half-holes 20 of condensers with the end in abutment with collar 31.

45 A casing 50 usually called a "can" is preferably made from metal and has a bottom wall 52 and side walls 54 with an open upper end.

An adjusting screw 60 threadedly engages the lower wall 52 and a lock washer 62 is in threaded engagement therewith, as shown.

In the assembled relation of the parts the lower end of tube 42 rests on the bottom wall 52 of can 50 and the upper end portion is disposed in half-holes 20 of the condensers 2 with the portion 34 of bushing 30 in the said upper end portion.

55 Holes 79 are provided in opposite walls 54 of can 50 to receive screws 72 engageable in tapped

holes 28 of bracket 22 for holding the parts in assembled relation as shown in Fig. 4.

Iron cores 66 and 68 are fixed to inner ends of the screws 36 and 60. As the screws are rotated in one direction or the other the cores are moved axially and being disposed within the tube 42 in the assembled transformer they are moved relative to the coils 44 and 46 for turning the same.

The components are arranged in compact and efficient relation while the screws are accessible for adjusting the iron cores. The condensers have interfitting parts on inner faces to hold them against relative shifting when in back to back relation and the novel holding means holds the assembly in the casing.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A transformer comprising in combination, a pair of condensers having inner faces in continuous relation, said inner faces provided with interfitting parts to prevent relative sliding movements of the condensers and having half-holes providing a central opening, a bracket extending across said condensers having side arms extending downwardly at the outer sides of the condensers, a bushing disposed in said central opening secured to said bracket that is internally threaded, a tube having its upper end in said central opening, coils on said tube, a casing having a lower wall and side walls enclosing said condenser, tube and coils with the said condenser at the upper ends of said side walls, screws in the internal threads of the bushing and in the said bottom wall extending into opposite ends of said tube, and iron cores on said screws in said tube.

2. A transformer comprising in combination, a pair of condensers having inner faces in contiguous relation, said inner faces provided with interfitting parts to prevent relative sliding movements of the condensers and having half-holes providing a central opening, a bracket extending across said condensers having side arms extending downwardly at the outer sides of the condensers, a bushing disposed in said central opening secured to said bracket that is internally threaded, a tube having its upper end in said central opening, coils on said tube, a casing having a lower wall and side walls enclosing said condenser, tube and coils with the said condenser at the upper ends of said side walls, screws in the internal threads of the bushing and in the said bottom wall extending into opposite ends of said tube, iron cores on said screws in said tube, and means securing said arms of the bracket to the walls of the casing.

3. A transformer assembly comprising in combination, a casing having a bottom wall and side walls extending upwardly therefrom, a pair of condensers in back to back relation between upper ends of opposite side walls, adjacent inner sides of the condensers provided with half-holes forming an axial central opening, a bracket hav-

ing an upper portion extending across the upper sides of said condensers, and side arms extending downwardly therefrom at outer sides of said condensers, a bushing carried by the upper portion of the bracket disposed in the upper portion of said opening, a central tube having its upper end in the lower portion of said opening and extending downwardly from the condensers and relative to the casing, coils fixed in spaced relation on said tube, and separate screws threaded in said bushing and in said lower wall provided with iron cores in said tube and related to said coils.

4. A transformer assembly comprising in combination, a casing having a bottom wall and side walls extending upwardly therefrom, a pair of condensers in back to back relation between upper ends of opposite side walls, adjacent inner sides of the condensers provided with half-holes forming an axial central opening, a bracket having an upper portion extending across the upper sides of said condensers, and side arms extending downwardly therefrom at outer sides of said condensers, a bushing carried by the upper portion of the bracket disposed in the upper portion of said opening, a central tube having its upper end in the lower portion of said opening and extending downwardly from the condensers and relative to the casing, coils fixed in spaced relation on said tube, and separate screws threaded in said bushing and in said lower wall provided with iron cores in said tube and related to said coils, inner adjacent faces of said condensers having interfitting portions holding them against relative sliding movements.

5. A transformer assembly comprising in combination, a casing having a bottom wall and side walls extending upwardly therefrom, a pair of condensers in back to back relation between upper ends of opposite side walls, adjacent inner sides of the condensers provided with half-holes forming an axial central opening, a bracket having an upper portion extending across the upper sides of said condensers, and side arms extending downwardly therefrom at outer sides of said condensers, a bushing carried by the upper portion of the bracket disposed in the upper portion of said opening, a central tube having its upper end in the lower portion of said opening and extending downwardly from the condensers and relative to the casing, coils fixed in spaced relation on said tube, and separate screws threaded in said bushing and in said lower wall provided with iron cores in said tube and related to said coils, inner portions of the half-holes in the condensers and the said bushing provided with interfitting portions to hold the condensers and bushing against relative sliding movements.

6. A transformer assembly comprising in combination, a casing having a bottom wall and side walls extending upwardly therefrom, a pair of condensers in back to back relation between upper ends of opposite side walls, adjacent inner sides of the condensers provided with half-holes forming an axial central opening, a bracket having an upper portion extending across the upper sides of said condensers, and side arms extending downwardly therefrom at outer sides of said condensers, a bushing carried by the upper portion of the bracket disposed in the upper portion of said opening, a central tube having its upper end in the lower portion of said opening and extending downwardly from the condensers and relative to the casing, coils fixed in spaced relation on said tube, and separate

screws threaded in said bushing and in said lower wall provided with iron cores in said tube and related to said coils, inner adjacent faces of the condensers having interfitting portions holding them against relative sliding movements, inner portions of the half-holes in the condensers and the said bushing provided with

interfitting portions to hold the bushing and condensers against relative sliding movements, and means extending through opposite side walls of the casing engaging the side arms of the bracket 5 whereby the said bracket, bushing and condensers are held against movement relative to the casing.

HOWARD J. BENNER.
